UNITED STATES PATENT OFFICE.

EUGENE BIVERT, OF CHICAGO, ILLINOIS, ASSIGNOR TO FAIRBANKS, MORSE AND COMPANY, OF CHICAGO, ILLINOIS, A CORPORATION OF ILLINOIS.

CAR-DUMP.

SPECIFICATION forming part of Letters Patent No. 779,391, dated January 3, 1905.

Application filed June 20, 1903. Serial No. 162,345.

To all whom it may concern:

Be it known that I, EUGENE BIVERT, a citizen of the Republic of France, and a resident of Chicago, in the county of Cook and State of Illinois, have invented certain new and useful Improvements in Car-Dumps; and I do hereby declare that the following is a full, clear, and exact description of the same, reference being had to the accompanying drawings, and to the letters of reference marked thereon, which form a part of this specification.

This invention relates more particularly to a device adapted to receive a loaded car or other vehicle therein and to unload the same by inverting or partly inverting the car.

Heretofore various types of car-unloading devices have been constructed, some of which operated by partly inverting the car. In most cases, however, the device was slow in operation, and the devices for securing the car in the cage or dumping apparatus frequently are slow in operation and insecure at the best, thus not only wasting considerable time in securing the car for unloading, but also rendering the operation more or less dangerous.

The object of this invention is to provide a construction in which the car can be quickly locked upon its track from movement and so constructed as to enable the car and its contents to be inverted with safety.

It is also an object of the invention to support the car on an axis in alignment with the center of gravity of the car and cage, thus obviating to a great extent the tendency of the car to a violent lateral movement, thus relieving the mechanism in great part, which would be due to an unbalanced condition common in constructions of the sort.

The invention consists in the matters hereinafter described, and more fully pointed out and defined in the appended claims.

In the drawings, Figure 1 is a top plan view of a device embodying my invention. Fig. 2 is a side elevation thereof somewhat broken. Fig. 3 is an end elevation of the same, showing the car secured in the cradle. Fig. 4 is a similar view, but showing the locking devices released from the car. Fig. 5 is a sec-

tion taken on line 5 5 of Fig. 2. Fig. 6 is an enlarged detail plan view with parts omitted, illustrating the hoists and operating mechanisms at one end of the construction. Fig. 7 is a fragmentary side elevation of the hoisting and operating mechanism inserted in Fig. 5. Fig. 8 is a section taken on line 8 8 of Fig. 6. Fig. 9 is an enlarged detail of the winch and connections for dumping the car. Fig. 10 is a section taken on line 10 10 of Fig. 9. Fig. 11 is an enlarged end elevation, partly in section, of one end of the cradle. Fig. 12 is a top plan view of the same. Fig. 13 is a bottom plan view thereof. Fig. 14 is a side elevation of the same. Fig. 15 is an enlarged detail, in side elevation, of the pivot-shaft and connections upon which the car and cradle turn. Fig. 16 is a section taken on line 16 16 of Fig. 15. Fig. 17 is a section taken on line 17 17 of Fig. 15. Fig. 18 is a top plan view of the same, showing same free from all the cable attachments or blocks excepting one. Fig. 19 is a top plan view of one of the cable-attaching blocks.

As shown in said drawings, a frame is constructed of structural iron or other suitable material comprising the uprights A, A', A², and A³, arranged opposite corresponding uprights A⁴. Said uprights or posts are connected longitudinally at the top by means of a plate a and transversely of the top by the beams a¹ a² a⁵ a⁶ and at a point below the track-level are connected by transverse sills a⁷ a⁸ a⁹ a¹⁰, as shown, supported on the beams A⁵ and A⁶, which extend longitudinally of the frame and are connected at their ends on the posts A A' A² A³ and the corresponding posts on the opposite side of the frame.

Supported on the sills a⁷ a⁸ a⁹ a¹⁰ and slideable longitudinally thereof are the upwardly-directed inner and outer pairs of supports B B', respectively, which, as shown, are shaped to receive and support the transverse segment-shaped members of a cradle upon which the car is supported during the dumping operation. Means are provided for sliding said knees B and B' oppositely from or toward the center of the frame, comprising, as shown, a screw-shaft b, provided at opposite ends from

the center with right and left threads and journaled at its ends, respectively, on the sill and the adjacent post. On the outer end of each screw-shaft is a bevel-gear b' , meshing 5 with a complementary bevel-gear b^2 , secured on a shaft b^3 , which extends longitudinally of the frame and is provided at its ends with hand-wheels b^4 to permit of manual operation. The 10 rotation of said shaft b^3 acts to drive all of said screw-shafts, shifting the knees or supports inwardly into supporting position for the cage or outwardly, as shown in Fig. 5, in position to permit the cage, with the car thereon, to swing clear. Said cage, as shown, 15 comprises transverse segment-shaped supports C , as shown, constructed of structural iron and adapted to rest on said knees and rigidly connected by means of longitudinal I-beams C' , having thereon track-rails continuous with 20 the tracks of the end of the frame. Connecting the adjacent pairs of cradle-segments on each side of the center and at each end of the cradle are the shafts C^2 . Said shafts, which are rigidly secured at their ends in said trans- 25 verse cradle-segments, act as rigid braces for each end of the cradle at the points on which the car-trucks are supported and also afford means for securing the car on said cradle, as shown in Figs. 2, 3, and 5. Secured on each 30 of said shafts C^2 are the collars d , having each an eye thereon in which a chain d' engages. Said chain is provided at its free end with a hook which engages in the eye d^2 of a turn-buckle D , one of which is rigidly but adjustably 35 secured at its upper end to each end of a transverse clamping-beam D' , adapted to engage across the top of the car and which is adjusted by means of said turnbuckles to rigidly clamp the same to the track. Pivottally secured near 40 the outer ends of said shafts C^2 are the outer and inner supporting-bars E and E' , each provided with a turnbuckle therein and having at the upper end a transversely-apertured head e , adapted to receive therethrough the shaft E^2 . Said 45 supporting-bars E and E' are of a length sufficient to extend upwardly and inwardly from said shafts C^2 , converging at a point approximately coincident with an axis drawn through the center of gravity of the loaded car and 50 the cradle, as shown in Fig. 3. The pivot-shaft E^2 is provided with a feather e' on each side thereof, as shown in Figs. 15 to 18, and slidably secured thereon are the blocks e^2 , which are provided on each side with a seat 55 to receive said feathers e' and through which said shaft passes. As shown, said block e^2 and the head of the turnbuckle-bars E and E' are arranged alternately on the shaft E^2 , and cables f f' are rigidly engaged at their ends 60 at opposite ends of said blocks and extend upwardly thereof over winches F , located at the top and each end of the frame. Said winches F , as shown, comprise the parallel longitudinal shafts F' F' , journaled on each 65 side of the frame at each end thereof on trans-

verse beams G and G' , which are supported transversely on the plate a . Each of said shafts is provided with grooved pulleys f^2 for the cables f f' . Means are provided for revolving said shafts, with the pulleys thereon, 70 oppositely, comprising brackets F^3 , supported on the beam G and through which the shafts F' pass. Journaled transversely at each end of the frame and at the top of said brackets is a rotative shaft H , having secured thereon 75 at the head of the brackets the right and the left worms h h' , respectively. Said worms each engage a complementary gear-wheel H' , carried on the shaft F' directly below the same and which acts to communicate the rotation of said worms to said pulleys. Means are provided for actuating the shaft H , comprising a gear h^3 , rigidly secured on one end thereof, and a pinion h^4 , journaled on the frame in mesh with said gear, is provided with 80 a crank h^5 , whereby said gear is actuated. Means are also provided for lifting the transverse clamping-beam D' , comprising a shaft H^2 , journaled on brackets h^6 , supported on the plate a , and provided with grooved pulleys h^7 , secured thereon, to which are attached the lines h^8 , provided with hooks at their extremities adapted to engage in eyes at the top of said clamping-beam D' , as shown in 85 Fig. 3. A gear-wheel h^9 is secured on one 90 end of said shaft H^2 , and a pinion h^{10} is journaled on the frame and meshes therewith and is provided with a crank h^{11} for actuating the same in a familiar manner, thereby enabling said clamping-beam to be manually raised or 95 lowered. For the purpose of enabling an operator at the crank h^{11} to aid in the operation of hoisting the car and cradle a bevel-gear I is secured on said shaft H^2 intermediate 100 the middle and near each end thereof, which meshes, respectively, with a complementary pinion i , rotatively secured on each of the shafts F' , near the end thereof. The hub of said bevel-gear i is shaped on its inner side to afford engagement with a clutch I' , feathered 105 on each shaft F' and slideable into or out of engagement with the hub of said bevel-pinions i by means of the arms i^2 , secured on a transverse shaft I^2 , one of which engages each clutch. A lever i^3 is provided at the end of 110 said shaft I^2 in position to be conveniently engaged by an operator at either crank. 115 Supported on the posts or uprights at one side of the frame is the laterally-projecting platform K , extending the entire length of 120 the frame and at a height to enable the operator to conveniently operate the winches F at the top and ends of the frame, secured on said uprights or posts. Horizontal shafts k k' are journaled on said uprights and provided at their ends in alignment with the transverse segments C C' with grooved cable-pulleys k^2 k^3 . The shaft k and pulleys k^2 are located near the top of the frame and on the outer sides of the posts, while the shaft k' 125 130

and pulleys h^3 are located below the cradle and on the inner side of the posts and cables h^4 are trained around said pulleys. One end of each cable passes upwardly and inwardly from the pulleys h^3 and is rigidly attached near the upper corner of the transverse segment member and the other end passes over the pulleys h^2 and extends downwardly and inwardly and beneath said segment, which is 5 grooved in its periphery to receive said cables, about which the ends of said lines engage as the cable is rotated. Secured on the shaft h is a gear-wheel h^5 , which meshes with a pinion h^6 , secured on a shaft h^7 , extending parallel with the shaft h and also journaled on said uprights, and a crank h^8 is secured upon the end of said shaft, thereby permitting the same 10 to be rotated manually with the effect of partly revolving the cradle.

15 The operation is as follows: The car-dump is erected at any desired point and with an inclined track-section (not herein shown) leading upwardly to each end of the cradle and registering with the track-rails laid thereon.

20 Said cradle is adjusted in register with said inclined track-section and supported upon the knees B and B' , as shown in Fig. 4. The clamping-beam D' is hoisted sufficiently high to avoid contact with the car when moved into 25 the cradle. When the car is in position on the track-rails of the cradle, said clamping-beam D' is lowered upon the top of the car and the chains d' are hooked into the eye d^2 of the turnbuckle at each end of said beam 30 and the turnbuckle adjusted up to bring considerable tension upon said beams, rigidly clamping the car to the cradle. While this is being done operators at each end of the car lower the shaft E' into position to be engaged 35 by the ends of the supporting-bars E and E' , which are swung upwardly and inwardly and secured on said shaft, as shown in Fig. 2. By means of turnbuckles forming a part of each 40 of said bars the length thereof may be adjusted so that the shafts E' at each end of the car lies approximately in alinement with an axis passing through the center of gravity of 45 the cradle and the loaded car. The cradle, with the car, is now ready for operation and 50 by means of the winches at each end of the frame the cradle is raised slightly or the knees or supports B B' are retracted laterally by means of the hand-wheels b^4 , so that the cradle and car are supported wholly upon the cables 55 f f' . An operator upon the platform K now partly rotates the cradle, with the car, by means of the winch h^8 provided for that purpose, as shown in Figs. 3, 9, and 10, said winch acting when turned in one direction to swing 60 the cradle to a dumping position, as shown in Fig. 5, and hold the same against any lateral throw occasioned by the dumping of the material therefrom and when rotated oppositely acts to return the same to the normal position. 65 The supports or knees B and B' are then moved

inwardly by means of the screw-shafts before described to the supporting position and the cradle lowered thereon, and chains d' are released from their connection with the clamping-beam D' and the lines h^8 are engaged into 70 the eyes on the top of said beam, which is elevated, as shown in Fig. 4, by means of the crank h^11 . The strain is released from the cable f f' sufficiently to permit the supporting-bars E and E' to be detached from the shaft 75 E^2 , and said bars are turned laterally outward and the shaft E^2 elevated to the position shown in Fig. 4, permitting the empty car to be run off the cradle. Obviously the operation of unloading the car may be very quickly performed 80 and with slight expenditure of power, owing to the fact that the loaded car and cradle are pivotally supported at or near an axis passing through the center of gravity. It is also obvious 85 that many details of construction may be varied without departing from the principles of this invention.

I claim as my invention—

1. The combination with a cradle, of means for rigidly securing a loaded car or the like 90 thereon, extensible connections pivotally secured at each side of the cradle at points adjacent to the car ends, a winch supported above the cradle, cables operated thereby and adapted for connection with said extensible connections near a longitudinal axis of and acting to support the cradle and car and means for partly rotating the cradle with the car secured thereon.

2. In a device of the class described the combination with a frame, of transverse beams therein laterally and oppositely adjustable knees on each side of the center of said beams, a cradle adjustably supported thereon, rotatable means acting to move said knees on each 100 side of the cradle oppositely into and out of supporting relation with the cradle, means for rigidly securing a car on said cradle, a winch located above the cradle and acting to support the cradle and car and means for partly 105 rotating the cradle with the car into dumping position.

3. The combination with a supporting-frame, of transverse beams therein, knees arranged in pairs on opposite sides of the center thereof, a cradle adjustably supported on said knees and adapted to support a loaded car thereon, means for rigidly securing the car on the cradle, bars pivotally engaged at each side of the cradle near each end thereof, 115 winches located above each end of the cradle, cables operated thereby and means for connecting said bars with said cables and with each other at an axis of the load and affording a pivotal support for the cradle and car and 120 means operating to rotate said cradle with the car to a dumping position.

4. The combination with a supporting-frame, of winches located at the top and at each end thereof, a cradle adapted to be sup- 130

ported at each end by said winches, a track-section thereon and means for rigidly securing a loaded car or the like on said track-section, a winch disposed at the side of the cradle and operating to partly rotate the cradle with the car to dumping position and to return the same to normal position and oppositely-movable supports beneath the cradle acting to normally support the same when in position to receive the car.

5. The combination with a supporting-frame, of winches at the top and each end thereof, a cradle supported at its ends from said winches, laterally-adjustable supports for said cradle, means for rigidly securing a loaded car on said cradle, a winch supported on the frame at the side of the cradle, cables operated therefrom and positively engaged on and acting to partly revolve the cradle and car to dumping position and to return the same to normal position.

6. The combination with a supporting-frame, of transverse beams therein, winches at the top and each end of said frame, a cradle adjustably supported thereon, means for rigidly securing a loaded car or the like upon the cradle, adjustable connections at the ends of the cradle adapted to be mutually engaged by the cables from said winches in axial alignment with the center of gravity of the cradle and car and means for partly rotating the cradle and car when supported on the winches to dumping position and returning the same to normal position.

35 7. The combination with a supporting-frame, of transverse beams therein, winches at the top and each end of said frame, oppositely-movable knees on said beams, means acting to move the same oppositely, a cradle 40 adjustably supported thereon, means for rigidly securing a loaded car or the like upon the cradle, adjustable connections at the ends of the cradle adapted to be mutually engaged by the cables from said winches in axial alignment with the center of gravity of the cradle and car and means for partly rotating the cradle and car when supported on the winches to dumping position and returning the same to normal position.

5c 8. The combination with a supporting-frame, of transverse beams therein, a cradle adjustably supported as to height thereon, a winch at each end of the frame, cables operated thereby, supporting-rods pivoted at the ends of the cradle and adapted to be swung upwardly and inwardly into engagement with said cables near the longitudinal axis of the cradle and car, adjustable means for locking the car to the cradle, pulleys journaled on the frame at one side of and above and below the cradle, cables arranged thereon and connected at their ends beneath and at opposite sides of the cradle and a winch connected therewith

and acting to partly rotate said cars and cradle to dumping position and to return the same therefrom.

9. The combination with a supporting-frame, of transverse beams therein, laterally-movable knees on said beams, a cradle adjustably supported as to height thereon, a winch at each end of the frame, cables operated thereby, supporting-rods pivoted at the ends of the cradle and adapted to be swung upwardly and inwardly into engagement with said cables near the longitudinal axis of the cradle and car, adjustable means for locking the car to the cradle, pulleys journaled on the frame at one side of and above and below the cradle, cables arranged thereon and connected at their ends beneath and at opposite sides of the cradle and a winch connected therewith and acting to partly rotate said cars and cradle to dumping position and to return the same therefrom.

10. In a device of the class described the combination with a frame, of transverse beams therein, a cradle adapted to be suspended within the frame, means for adjustably supporting said cradle as to height comprising a plurality of upwardly-directed laterally-movable knees arranged on said transverse beams on opposite sides of the cradle, a screw-shaft oppositely threaded from its center and extending above and parallel with said beams and having threaded engagement in apertures in said knees and means for rotating the said shaft acting to draw said knees outwardly from the cradle or to force the same beneath the cradle.

11. The combination with a frame, of transverse beams thereon, a screw-shaft journaled above and parallel with the beams, laterally-disposed knees through which said screw-shaft extends and in which the same has threaded engagement, a bevel-pinion at the outer end of each screw-shaft, a shaft extending longitudinally of the frame, beveled gears thereon complementary with those on the screw-shafts and means for rotating said shaft acting to move the knees oppositely from or toward the centers of the beams, a cradle normally supported on said knees and having a convex base engaging on said knees and adjustable as to height thereby.

12. In a device of the class described, a cradle provided on its ends on each side thereof with a longitudinal shaft, turnbuckles pivotally engaged on the ends of said shafts and adapted to be swung upwardly and inwardly and shaped at their upper ends for engagement with a hoisting device.

13. In a device of the class described, a cradle provided on its ends on each side thereof with a longitudinal shaft, turnbuckles pivotally engaged on the ends of said shafts and adapted to be swung upwardly and inwardly and shaped at their upper ends for engagement

with a hoisting device and winches located above the cradle and acting to lift the same by said turnbuckles.

14. The combination with a cradle, of chains secured at the sides and ends thereof, clamping-beams supported above the same, a turnbuckle depending at each end of each clamping-beam and adapted at its lower end for engagement with said chains and a winch for lifting the clamping-beams.

15. The combination with a cradle, of a winch at each end thereof above the same, acting to lift the cradle a clamping-beam, a winch for lifting the same and adjustable means whereby said winch for the clamping-beam may be operated conjointly with the other winches for lifting the cradle.

16. The combination with a frame of a cradle, supports therefor adjustable laterally of the frame, a winch on the top of the frame at each end of the cradle, a shaft extending longi-

tudinally of the cradle and connected therewith and cables connecting said shaft with said winches and means for clamping a car on said cradle.

17. The combination with a rigid frame of a plurality of knees thereon, means adapted to move said knees laterally and oppositely, a segment-cradle adapted to be supported on said knees, means for clamping a car thereon, a longitudinal shaft at each end of the cradle adjacent each side thereof, extensible bars pivoted thereon, a plurality of winches, cables connecting said bars with said winches and means for partially rotating the cradle.

In testimony whereof I have hereunto subscribed my name in the presence of two subscribing witnesses.

EUGENE BIVERT.
